UNITED STATES PATENT OFFICE

2,670,417

PRESSURE RESPONSIVE SWITCH

Estel C. Raney, Delaware, Ohio, assignor to
Ranco Incorporated, Columbus, Ohio, a corpora-
tion of Ohio

Original application August 3, 1948, Serial No.
42,177, now Patent No. 2,556,981, dated June 12,
1951. Divided and this application March 26,
1951, Serial No. 217,580

4 Claims. (Cl. 200—83)

1

The present invention relates to a controller and is herein illustrated as an electric switch of the pressure operative type. This application is a division of my co-pending application Serial No. 42,177, filed August 3, 1948, now Patent No. 2,556,981.

More specifically the present invention relates to a controller which is formed from a plurality of sub-assemblies, each of which includes a wall, and which when assembled form a housing with the control mechanism enclosed therein.

For the purpose of distinguishing one wall from another, the word "top" and the word "bottom" have merely been used for the purpose of explanation in connection with the location of the parts in the drawings. It is to be understood that the controller is capable of being placed in various positions. For example, the top wall may be the bottom wall.

For example, if the switch were inverted, the top wall would be the bottom wall with no changes in the physical structure of the controller. In other words the words "top" and "bottom" are merely used as means of distinguishing one wall from the other.

In carrying out the present invention, the bottom sub-assembly includes a housing wall having an opening for receiving a cam follower. This sub-assembly also includes a cam and mechanism for turning the cam. An upper sub-assembly includes a top housing wall and certain control mechanisms. The control mechanism herein shown comprises snap acting mechanisms for actuating a movable contact. The top and bottom sub-assemblies are connected with one another through side plates or walls. A third or end sub-assembly includes an end wall for closing one end of the structure formed by the top and bottom walls and the side plates. This third sub-assembly includes a sealed expandable and contractible element or aneroid. A plurality of levers are pivotally connected with the side plates. One of these levers is operatively associated with the aneroid and the snap acting mechanism for actuating the snap acting mechanism in response to movement of the aneroid. The other lever is also pivotally connected to the side plates and is connected to the first mentioned lever through a spring. The second mentioned lever has a cam follower which extends through an opening in the bottom wall and is arranged in co-operative relation with the cam carried by the bottom wall whereby the tension of the spring can be regulated so as to selectively control the pressure at which the snap acting mechanism functions.

2

In the specific embodiment of the invention, each of the side plates is provided with at least one opening for receiving projections or ears formed integrally with the top wall so as to locate the position of the top wall with respect to the side plates. The top wall is also provided with inwardly extending ears and the side plates are also provided with inwardly extending ears. The side plate is formed of flexible material such as sheet metal and the ears of the side plates are wrapped around the ears of the top wall so as to hold the top wall and side plates in position. Each of the side plates is provided with a pair of confronting shoulders adjacent an end edge thereof and these shoulders form guideways. The end wall of the end sub-assembly is held in position by the guideways so as to locate the end sub-assembly in position. The top wall and the bottom wall each have a portion which overlie the top and bottom respectively of the end wall to prevent accidental displacement of the end wall.

The bottom wall of the bottom sub-assembly is provided with a plurality of bayonet type slots. 25 These slots co-operate with integrally formed ears on the side plate for latching one end of the bottom sub-assembly in position. The other ends of the side plates and bottom wall are suitably connected as by screws.

30 As previously pointed out the side plates are formed of flexible material preferably of sheet metal. Also as previously stated, the levers are pivotally mounted on the side walls. In order to re-enforce the material adjacent the pivot point of the levers, the material adjacent the openings which receive the pivots for the lever, is corrugated.

35 Further objects and advantages of the present invention will be apparent from the following description, reference being had to the accompanying drawings wherein a preferred form of embodiment of the invention is clearly shown.

In the drawings:

Fig. 1 is a side view, partly in section, of a 40 controller and the improved housing therefor;

Fig. 2 is a side elevational view of the housing containing the control mechanism;

Fig. 3 is a perspective view of part of the controller housing;

Fig. 4 is a perspective view of the end sub-assembly;

Fig. 5 is a fragmentary perspective view of the right end of the controller;

Fig. 6 is a bottom view of the controller, one 55 of the retaining ears of a side plate being broken away to show one of the bayonet slots, in the bottom wall, which receives one of the ears; and

Fig. 7 is a fragmentary sectional view of the side plate and mounting bracket for the housing, the section being taken on line 7—7 of Fig. 2.

Referring to the drawings, the controller 20 is formed principally of several interconnected and co-operated sub-assemblies. The top wall of the controller is formed of an upper sheet or panel 22 and a lower sheet or panel 23 or resinous material such as phenolite. These sheets are suitably attached to one another and are held in position with respect to the side plates 90 and 91 by ears or projections 24 which extend through perforations 24a, as seen in Fig. 3 of the side plates.

Terminals 25 and 26, formed of electrical conducting material extend through the sheets 22 and 23. The lower end of the left terminal 25 is provided with a horizontally extending portion 27 which serves as a seat for a stationary contact 28. The lower end of the right terminal 26 is provided with a horizontally extending arm 29, forming a lower stop for a leaf spring 34. A co-operating contact 33 is carried by a leaf spring 34. The leaf spring is provided at the right end with an up turned portion riveted at 35 to a portion of the terminal 26 which is located below the top sheet 21.

A snap acting mechanism is provided for moving the spring 34 to either open or close the contacts with a snap action. This mechanism includes a toggle assembly having a link or toggle member 40 and a spring, herein shown as a flat U-shaped spring 41. Both the link 40 and the spring 41 are carried by the spring 34 and provide for actuating the spring 34 in either of two directions, that is either up or down as viewed in Fig. 1. The leaf spring 34 has an upwardly extending projection having an opening or window 55 through which the link 40 extends and which provides in effect a loop by which the toggle can be moved up or down and cause snap actuation of the spring 34 as is described in detail in my U. S. Patent No. 2,556,981.

From the foregoing it will be seen that the connected top walls 21 and 22, the contacts 28 and 33 and the snap acting mechanism for contact 33 form a top sub-assembly.

The snap acting mechanism is actuated in one direction by an expansible and contractible sealed element, such as an aneroid 70 through a lever assembly 60. This lever assembly includes a lever 61 having a pair of tines 61a; only one of which is shown, each of which merges into a shoulder portion or pivot 62 at their ends. One of these shoulders extends through an aperture 61b of plate 90 and the other extends through a like aperture of plate 91. The left side walls 61c of the metal surrounding and defining the aperture 61b form bearings for pivots 62. The left end of the lever 61 carries a flat plate of insulating material 63, such as phenolite. The top of this plate 63 is arranged to abut the lower end of spring 34 for moving the spring 34 upwardly upon expansion within the aneroid 70.

The operation of the snap acting device is clearly defined in the above mentioned co-pending application. For the purpose of the instant case, it is sufficient to state that the spring 34 is biased to exert a pressure downwardly to snap the link 40 and the spring 41 through dead center position by means of the loop 55, to separate contact 33 from contact 28, when the upward pressure of the lever 60 has been decreased to a predetermined value, and the upward movement of the spring 34 through the loop 55, will snap the link 40 and the spring 41 through dead

center position to close the contact 33 on contact 28 when the upward pressure exerted by lever 60 on the spring 34 has increased to a predetermined value.

The pressures at which the snap acting mechanism actuates the contact 33 is governed by a spring 66. This spring is connected at one end to an extension 65 of lever 60 by an adjustable screw 67. The other end of the spring 66 is connected to arm 75a of a lever 75. Lever 75 is provided with a plurality of tines 75b, only one of which is shown in Fig. 1. These tines merge into shoulders 75c (see Fig. 2), each of which extends through an opening 75d of one of the side plates 90 and 91, the wall defining the aperture 75d forming a bearing for a tine 75c. The lever 75 also includes a downwardly extending portion 78 which forms a cam follower which extends through an opening 82 in the bottom wall 85 of the bottom sub-assembly.

In addition to the wall 85, the bottom sub-assembly includes a rotatable cam 81. Cam 81 is actuated by a cam driver 80 suitably secured to the cam. This cam driver 80 extends into a knot 86b of an operating knob 86a. This operating knob is carried by a shaft 86 which latter is journaled in the bottom wall 85.

The left end of plate 85 is provided at the front end with bayonet type slots 90c, each of which is arranged to receive downwardly and then inwardly extending ear 90b formed integrally with the side walls 90 or 91. In placing the bottom cover 85 in position, the bottom cover 85 is moved to a position to receive the ears 90b in the enlarged openings in the apertures 90c and then the bottom 85 is moved to the left so that the bottom part of the ears 90b overlaps the bottom wall 85 as is clearly shown in Fig. 6. The bottom wall 85 is secured in position with respect to the side plates 90 and 91 by two screws 95. These screws 95 extend upwardly through the bottom plate 85 and are threaded into inwardly extending ears 94. These ears 94 are formed by shearing the lower edges of each of the plates 90 and 91 and then bending the parts intermediate the shearing, inwardly.

The end sub-assembly includes, in addition to the aneroid 70 an end wall 98. The aneroid 70 is carried by the wall 98, it being hermetically sealed to wall 98 as at 98a. The left wall of the aneroid 70 carries a bearing plate 71 which abuts the right end of the first class lever 61. The end sub-assembly also includes a tube 101 which is hermetically sealed to the end wall and is in open communication with the interior of the aneroid 70. This tube and the aneroid is part of a closed thermostatic system containing a liquid or gas or a combination of the two. In the instant application the controller is particularly useful in connection with the thermostatic control of a refrigerating system in which the contacts 33 and 28 control the operation of the motor for the refrigerating system. The end sub-assembly is held in position by guideways formed of shoulders. The right end of said plate 90 is provided with an inwardly extending flange 96 and a similar flange 97 is formed on plate 91. The side walls 90 and 91 are also pierced and bent inwardly adjacent the flanges 96 and 97 to provide shoulders 96a which confront the shoulders formed by the left side of flanges 96 and 97. The shoulders co-operate to form a guideway for receiving the front and rear edges of the wall 98. As seen in Fig. 5, the right end of the top sheet 21 of the top wall overlies the upper edges of wall 98 so as to prevent upward

displacement of the end sub-assembly. And it will also be seen from Fig. 1 that the wall 85 overlies the lower end of the wall 98 of the end sub-assembly to prevent downward displacement of the sub-assembly. Thus the shoulders formed by the walls 90 and 91 and the overlying portions of the top wall 21 and bottom wall 85 lock the end sub-assembly in position.

The left side wall 100 may be formed of transparent material such as glass. It is held in position in the same manner as wall 98. However, the ledge or shoulder 99 which functions the same as the shoulder 96a, is formed by forming inwardly bulged portions on the side plates 90 and 91.

To assist in holding the side plates 90 and 91 and the top wall in position, integrally formed ears 23a extend toward the end and integrally formed ears 98 on the plates 90 and 91 extend around the ears 23a, as is clearly shown in Fig. 3.

Since the side plates are formed of thin flexible material, it is desirable to reinforce the side plates adjacent the bearings for the levers 61 and 75. To accomplish this a corrugation 103 surrounds the openings 61b and 75d whose walls 25 form the bearings for said levers.

From the foregoing it is readily apparent that I have materially simplified the construction of a controller and materially reduced the cost of manufacture including the assembly of the controller. This controller comprises principally three sub-assemblies, each of which includes one of the walls of the housing of the controller.

While the form of embodiment of the present invention as herein disclosed constitutes a preferred form, it is to be understood that other forms may be adopted, all coming within the scope of the claims which follow.

I claim:

1. In a control apparatus, a housing comprising two oppositely disposed side walls; a control device actuating lever pivoted between said walls adjacent to one end of the housing and having a part extending toward the other end of the housing; an arm pivoted between said walls adjacent to said one end of the housing and having a part extending laterally of said lever; a spring interconnecting said parts of said lever and arm to oppose movement of said lever in one direction, said walls having shoulders at said one end of said housing facing inwardly of said housing; a pressure responsive device comprising a plate and an expansible element on said plate, said plate abutting said shoulders to hold said element in engagement with said lever to urge said lever in one direction; a closure member attachable to said housing and extending between said walls, said closure member having a part extending over an edge of said plate to retain said plate in engagement with said shoulders; and means on said closure member to vary the position of said arm about its pivot and change the tension of said spring.

2. In a control apparatus, a housing comprising two oppositely disposed side walls; a control device actuating lever pivoted between said walls adjacent to one end of the housing and having a part extending toward the other end of the housing; an arm pivoted between said walls adjacent to said one end of the housing and having a part extending laterally with respect to said lever; a spring interconnecting said parts of said lever and arm and opposing movement of said lever in one direction; means for-

ing guideways at said one end of said housing to slidably receive a plate; a pressure responsive device comprising a plate slidably positioned in said guideways and an expansible element on said plate engaging said lever to urge said lever in said one direction; a closure member attachable to said housing and extending between said walls, said closure member having a part extending over an edge of said plate to retain said plate in said guideways; and means on said closure member to vary the position of said arm about its pivot and change the tension of said spring.

3. In a control apparatus, a housing comprising two oppositely disposed side walls, a control device at one side of said housing and extending between said walls; a control device actuating lever pivoted between said walls adjacent to one end of the housing and having a part extending toward the other end of the housing and engageable with said control device; an arm pivoted adjacent to said one end of the housing and having a part extending laterally of said lever and toward the side of said housing opposite said one side; a spring interconnecting said parts of said lever and arm to oppose movement of said lever in one direction; a pressure responsive device comprising a plate closing said one end of said housing, and an expansible element on said plate and engaging said lever to urge said lever in one direction; a closure member attached to said opposite side of said housing and extending between said walls; and means on said closure member arranged to shift said part of said arm to vary the position of said arm about its pivot and change the tension of said spring.

4. In a control apparatus, a housing comprising two oppositely disposed side walls; a control device at one side of said housing and extending between said walls; a control device actuating lever pivoted between said walls adjacent to one end of the housing and having a part extending toward the other end of the housing and engageable with said control device; an arm pivoted adjacent to said one end of the housing and having a part extending laterally of said lever and toward the side of said housing opposite said one side; a spring, interconnecting said parts of said lever and arm to oppose movement of said lever in one direction; a pressure responsive device comprising a plate closing said one end of said housing, and an expansible element on said plate and engaging said lever to urge said lever in one direction; a closure member attached to said opposite side of said housing and extending between said walls, said closure member having an opening through which said part of said arm extends; and a cam on said closure member engaged by said part of said arm to vary the position of said arm about its pivot and change the tension of said spring.

ESTEL C. RANEY.
